UNITED STATES PATENT OFFICE.

CLARK L. SMITH, OF SPOKANE, WASHINGTON, ASSIGNOR TO SPOKANE CASKET COMPANY, OF SPOKANE, WASHINGTON, A CORPORATION.

CRUSHING MACHINE.

Application filed April 13, 1925. Serial No. 22,730.

To all whom it may concern:

Be it known that I, CLARK L. SMITH, a citizen of the United States, residing at Spokane, in Spokane County and State of Washington, have invented certain new and useful Improvements in Crushing Machines, of which the following is a specification.

The present invention relates to improvements in Crushing Machines of the type employed for fashioning tufts or ornamental irregularities in textile material or fabric, such as material used in lining caskets etc. The machine is employed in connection with hand stitching for securing the backing on the crushed fabric while the latter is in the machine, and the invention is designed for the purpose of increasing the production and efficiency as well as reducing the expense involved in time and labor employed and required. To accomplish this purpose I utilize a bodily tiltable main frame and a relatively tiltable supporting frame for the crushing rods, whereby the parts may with facility be manipulated in the progress of the work.

The invention consists in certain novel combinations and arrangements of parts as will hereinafter be more fully set forth and claimed.

In the accompanying drawings I have illustrated one complete example of the physical embodiment of my invention wherein the parts are combined and arranged according to the best mode I have thus far devised for the practical application of the principles of my invention.

Figure 1 is a top plan view of a machine embodying my invention.

Figure 2 is a detail sectional view enlarged at one end of the machine.

Figure 3 is a detail end view at one corner of the rectangularly shaped machine.

Figure 4 is a side elevation of the machine showing the table with the crushing frame in full and dotted lines, and the crushing rods and their holder also tilted to dotted line position.

Figure 5 is a detail perspective view showing the crushing rods and their holder and other features of the device.

In carrying out my invention I utilize a rectangular supporting table 1 with legs 2 upon which the rectangular crushing frame is pivoted, as at the rear of table so that it may be tilted up to dotted line position in

Figure 4 for the removal of the completed material. The bodily tiltable crushing frame carries a rod holder which is also tiltable with relation to the frame, for the purpose of removing all of the crushing rods simultaneously from the completed material.

The rectangular crushing frame is made up of suitable material and in desired sizes to accommodate various widths of material and said frame comprises a pair of side bars 3 arranged along the opposite parallel ends of the table. A pair of brackets 4 are fastened at opposite ends of the table at the rear corners and these side bars of the frame are pivoted at 5 in the brackets. The crushing frame normally lies flat upon the top of the table and is provided with a pair of parallel spaced supporting plates 6 which extend from the front to the rear of the frame, and above these inwardly projecting plates 7 are spaced top retaining and guide plates 8 secured to the side bars 3 of the frame and forming a part thereof. The rectangular crushing frame is completed by the use of a pair of bars 9 at the front and rear to form a rigid structure pivoted or hinged at 10 above the table.

Within the crushing frame is carried a series of transversely extending slats 10 each having slide ends 11 located between the bottom plates 6 and the retaining plates 8, and a guide shoulder 12 is fashioned at each end of each slat for co-action with the inner edge of the retaining plates 8. All of the slats are connected together by means of a flexible strip or strips as indicated at 13, which is preferably made up of suitable tape or webbing secured at the undersides of the slats. The slats are normally spaced apart on the webbing or tapes so that they may be slid together to close the frame when the material M is to be crushed, or separated one from another after the completed product has been removed from the frame.

For closing or opening the crushing frame I use an end bar 14 preferably of angle iron, to which the connecting tapes are secured, at their ends. This bar has a pair of spaced handles 15 attached thereto for facility in manipulating it, and it will be understood that the frame is closed by pushing the bar to successively close up the gaps between the slats, and the frame is opened by pulling the bar to successively open the gaps between the slats. In this movement the slats

are retained in relative position and guided by the bottom and upper guides 6 and 7 at each side of the frame and table.

Along their upper edges the slats are beveled as at 16 to prevent the material M being caught between the slats.

Each slat carries a row of headed pins 17 projecting a suitable distance above its upper surface and the pins are arranged on the 10 slats so that the pins of successive slats are in staggered formation but spaced apart at uniform intervals, for use in fashioning the crushed appearance on the fabric or material M.

15 Each slat also carries a row of pointed studs 18 which are considerably shorter than the headed pins in order that the material may be supported on the frame in such manner that the pointed studs will not be in the 20 way of the hands of the stitcher when bast- ing the backing on the material.

As seen in Figure 2 the material is placed upon the headed pins while the crushing frame is open, that is the slats are spaced 25 apart, and the material between the headed pins is pushed down over the protruding pointed studs so that the latter penetrate and pass through the material.

The rods 19 are then placed in position 30 in pairs, the rods of each pair being located at opposite sides of the aligned rows of studs on the slats, and the pair of rods located between staggered headed pins of the slats. With the parts in this position the rods are 35 successively placed on top of the material being crushed as the work proceeds.

The rods 19 are carried in a tiltable holder arranged transversely at the rear end of the machine and carried by the crushing frame. 40 This holder comprises a pair of complementary plates 20 and 21 that may be clamped together by means of bolts 22 and wing nuts 23, and the ends of the holder are fashioned with trunnions or pivot pins 45 24 supported in brackets 25 secured to the crushing frame. By means of a crank handle 26 at either end of the machine the holder may be turned on its trunnions for tilting the rods which are carried in pairs 50 of sleeves 27 fashioned in the holder. These sleeves extend transversely of the holder and may be secured in their sleeves by turning the clamp nuts 23 to bind the plates 20 and 21 together. During the process of 55 crushing the material, however the nuts are loosened in order that the rods in pairs may be slid through their sleeves to proper position on the material. After all the rods have been placed in position to perform 60 their functions of crushing the material and with the rods clamped in the holder and the material has been properly fashioned,

the holder may be turned to remove bodily all of the rods from the material. Then the 65 backing is placed on the crushed material and stitched or basted in usual manner.

To get the rods out of the way, after the clamp plates have been loosened, the rods may be slid through their sleeves down upon an apron 28 having a lower stop strip or 70 abutment 28'. This apron is hinged at 29 to the table and may be turned back under the table top when not in use and retained by a latch 30 and its keeper 31 on the apron and table respectively. When in extended 75 position the apron may be held as in Figure 4 by means of a supporting bar 32 hinged to the apron at 33, and a spring 34 on the bar is used as a resilient support for the apron.

In Figure 1 it will be seen that the rods abut against the push bar 14. With the clamp plates loosened, when the crushing frame is closed by pushing upon the bar 14 it will be apparent that the rods are pushed with their ends extended through their sleeves, as indicated by dotted lines in Figure 4. In this position the rods may be manipulated singly, or all the rods may be tilted when the holder is turned on its trunnions. Before removing the finished product the crushing frame may be tilted to permit the loose rods to slide through their sleeves to the apron, after which the finished product is removed with facility.

Having thus fully described my invention, what I claim as new and desire to secure by Letters Patent is—

1. The combination with a main frame and flexibly connected slats therein, of a 100 tiltable holder parallel with the slats, crushing rods arranged in pairs and carried by said holder for co-action with the slats, and means for clamping said rods in the holder.

2. The combination with a main frame and flexibly connected slats therein, said slats having each a row of headed pins, and shorter studs carried by said slats in aligned rows transversely of the slats, of a tiltable holder carried by the main frame, crushing rods arranged, in pairs and carried by said holder, said rods adapted to rest at opposite sides of said aligned rows, and means for clamping the rods in the holder.

3. The combination with a table, of a hinged crushing frame, a series of flexibly connected slats having headed pins and shorter pointed studs, a tiltable holder on said frame, pairs of crushing rods carried, by said holder for co-action with the studs, and means for clamping the rods in the holder.

In testimony whereof I affix my signature.
CLARK L. SMITH.
